Frank H. Lewis
ATTORNEY

UNITED STATES PATENT OFFICE

WILLIAM NELSON, OF BLOOMFIELD, NEW JERSEY, ASSIGNOR TO BURNETT WALKER,
OF NEW YORK, N. Y.

RADIATOR CAP

Application filed June 19, 1928, Serial No. 286,509. Renewed October 8, 1932.

My invention relates to radiator-filling fittings or structures, especially adapted to automobile radiators.

The general object is to provide a filler-fitting or "cap" which is located in a front, upper portion of the radiator or radiator-shell, below the top thereof, thus avoiding the customary filling tube or cap which projects above the radiator, interferes with vision of the driver, causes spillage to flow upon and soil or damage the "finish" of the radiator-shell and engine hood, and has various other disadvantages, as understood by persons skilled in the art.

15 A further object is to arrange the front plate or cover of the filling fitting as an emblem support, or to combine an emblem therewith.

The characteristics and advantages of the invention are further sufficiently explained in connection with the following detail description of the accompanying drawing, which shows one preferred embodiment. After considering this example, skilled persons will understand that many variations 25 may be made, and I contemplate the employment of any structures that are properly within the scope of the appended claims.

30 In the drawing:

Fig. 1 is a front elevation of the upper, central portion of an automobile radiator, with the invention, in one form, incorporated therein.

35 Fig. 2 is a section at 2—2, Fig. 1.

Fig. 3 is a similar section, showing a different operative position.

The radiator includes the usual core 1, top tank 2, and shell 3. The tank and shell have 40 in their front walls, usually centrally in respect to width of the car, apertures 4 and 5 respectively to receive the filler-fitting.

This fitting consists of two main parts, a body or frame 6 and a filling trough 7 hinged-45 ly connected thereto at 8. The frame has portions overlapping top and front margins of the tank adjacent its aperture, and secured thereto, as by rivets 9. At the top of the frame is a lug 10 apertured to receive 50 a loop-hasp or latch 11.

Trough 7 includes a front wall or cover 7^a, rearwardly extending side walls 12 and a bottom wall 13. The latter, and the upper edges of the sides walls, are arcuately curved, on a radius struck from the hinge center. The rear edge of the bottom wall is down curved to form a stop 14, cooperating with the lower portion of the frame to retain the trough in proper "open" or filling position (Fig. 3). Near its edges the cover plate has in its rear face a channel 15, retaining a gasket 16, which, when the trough is in closed position, (Fig. 2) engages the front edge 17 of the frame and seals the opening. A lug 18 projects from the upper edge of the cover plate, to cooperate with hasp 11 and retain the cover and trough in closed position, and also serves as a handle.

The front plate also desirably serves as an emblem support. Any desired symbol, emblem, or a plate carrying the same, may be attached to plate 7^a; or as shown, the emblem such as 20 may be applied directly to the plate.

75 The mode of operation is obvious in the positional views.

The relatively low location of the filling trough makes it correspondingly easy to fill the radiator by pouring from a bucket, or inserting the nozzle of a hose into the trough. At the same time the water level is easily observed through the trough, and overflow can usually be avoided; but any overflow caused by overfilling or by overheating of the radiator, will fall in front of the same, where it is least objectionable, and cannot run upon and injure the top of the shell or the hood.

80 This invention is, in its broader aspects, similar to that disclosed in my application Serial No. 282,225; but in distinction therefrom, provides a trough which opens by pivotal movement, and is in some respects and for some purposes, preferable to the sliding or telescoping trough shown in said application.

90 I claim:
1. In combination with a radiator tank and shell having apertures in front vertical 100

- walls and below the tops thereof; a filling fitting comprising a frame secured to the tank wall about its aperture; and a trough pivotally connected to the frame, said 5 trough comprising a front wall member adapted to receive an emblem and approximately closing the shell aperture; side walls, and an arcuate bottom wall; a stop at the rear of the arcuate bottom wall and adapted 10 to cooperate with the frame and retain the trough in open position; and locking means comprising an upwardly extending lug attached to said front member, said lug forming a handle for opening the trough.
- 15 2. The combination of a radiator tank and shell having spaced vertical front wall portions below the tops thereof with substantially aligned apertures in such portions; a filling fitting frame secured to the 20 tank wall and extending forwardly therefrom; a closure pivoted to said frame on a substantially horizontal axis, said closure being adapted to seal against said frame in closed position and to incline forwardly and 25 upwardly in open position; and a filling trough extending rearwardly from said closure, said trough having a bottom portion which when said closure is open extends through the space between said vertical walls and into said tank.
- 30

In testimony whereof I affix my signature.
WILLIAM NELSON.
